UNITED STATES PATENT OFFICE.

NORA B. SPOONER, OF WARREN, NEW HAMPSHIRE.

WRINGER-STAND.

No. 878,682.

Specification of Letters Patent.

Patented Feb. 11, 1908.

Application filed October 16, 1907. Serial No. 397,632.

To all whom it may concern:

Be it known that I, NORA B. SPOONER, a citizen of the United States, residing at Warren, in the county of Grafton and State of New Hampshire, have invented a new and useful Wringer-Stand; and I do hereby declare the following to be a full, clear, and exact description of the invention, such as will enable others skilled in the art to which it appertains to make and use the same.

This invention relates to a new and useful wringer stand, upon which washing tubs are supported; especially the invention comprises an attachment for the stand, whereby a third tub for receiving dry clothes is supported.

This invention comprises further objects and combinations of elements which will be hereinafter more fully described, shown in the accompanying drawings, and the novel features thereof will be pointed out by the appended claims.

To obtain a full and correct understanding of the details of construction, combinations, features, elements and advantages, reference is to be had to the hereinafter set forth description and the accompanying drawings in connection therewith, wherein

Figure 1 is a side elevation of a wringer stand showing the improved attachment applied thereto. Fig. 2 is a perspective view of a portion of said stand, showing the attachment applied thereto, so as to illustrate more in detail the construction thereof. Fig. 3 is a view of a portion of the stand, showing the coupling member in position, so as to facilitate the connection of the attachment. Fig. 4 is a view of the coupling member showing the same ready to be attached to a portion of the stand.

Like numerals of reference indicate like parts throughout the several views.

In regard to the drawings 1 designates the wringer frame having a wringer apparatus 2, as shown and provided with a pair of foldable members 3 and 4, which are provided with hinged supporting legs 5 and 6, as clearly shown. The said legs are hinged by means of rods 7 and 7^a extending the entire width of the members 3 and 4, the latter of which rods is fixed non-rotatably with relation to the said member 4, so as to prevent disconnection of the third tub supporting attachment 8, as will be observed. The third tub supporting attachment consists of a pair of foldable members 9 and 10,

the member 10 being pivoted as at 11 to the lower portion of the member 9, while the member 9 is provided with lugs 12 to be engaged by the member 10, to limit the downward oscillatory movement thereof. The member 9 is provided with a rod 13, upon which sleeves 14 are disposed, and between which sleeves the coupling member 15 is received, when the third tub supporting attachment is connected to the member 4, as will be clearly seen in the drawings.

The rod 7^a is provided with slots 16 to receive the extensions 17 of the coupling member 15, which is of a circular form and provided with a resilient lip 18, which holds the rod 13 in place, as shown. To prevent removal of the coupling a U-shaped member 19 is provided to engage openings 20 of the extensions 17, as clearly shown.

It is to be understood that various changes and modifications may be employed in the construction and embodiment thereof, combinations of features, and elements, without in any way departing from the spirit of the invention covered by the claims, thereof; which variations or modifications if employed must fall within the scope of the appended claims.

From the foregoing, the essential features, elements and the operation of the device, together with the simplicity thereof, will be clearly apparent.

Having thus fully described the invention, what is claimed as new and useful by the protection of Letters Patent, is:—

1. In a device as set forth, a wringer frame having fixed thereto a wringer and provided with a pair of foldable members, one of said members having a non-rotatable rod, a coupling carried thereby, a foldable third tub supporting device supported by said coupling comprising foldable members, one of which being provided with means to prevent downward oscillatory movement of the other member thereof.

2. In a device as set forth, a wringer frame having a pair of foldable members, one of which being provided with a non-rotatable rod having a pair of slots, a coupling having a pair of extensions designed to engage said slots of said rod, means to prevent removal of said coupling and a third tub supporting device supported by said coupling.

3. In a device as set forth, a wringer frame, a wringer fixed thereto, said frame

having a pair of foldable members, one of which being provided with a non-rotatable rod having a pair of slots, a coupling having a pair of extensions having openings designed to engage said slots of said rod, a U-shaped member to engage the openings of said extensions, a foldable third tub supporting device supported by said coupling comprising foldable members, one of which being provided with means to prevent downward movement of the other member thereof.

4. In a device as set forth, a wringer frame having a pair of foldable members, one of which being provided with a non-rotatable

rod having a pair of slots, a coupling having a 15 pair of extensions having openings designed to engage said slots of said rod, a U-shaped member to engage the openings to prevent removal of the coupling, and a third tub supporting device supported by said coupling. 20

In testimony whereof I have signed my name to this specification in the presence of two subscribing witnesses.

NORA B. SPOONER.
